CLAIM

I claim the ornamental design for a 9mag .22 L.R subsonic reticle, as shown and described.

DESCRIPTION

FIG. 1 is a side view of a 9mag .22 L.R subsonic reticle showing the new design having a 9x illuminated view;

FIG. 2 is a front view of a 9mag .22 L.R subsonic reticle thereof having a 9x illuminated view; and,

FIG. 3 is a perspective view of a 9mag .22 L.R subsonic reticle thereof having a 9x illuminated view.
